UNITED STATES PATENT OFFICE.

PETER S. H. NEWELL, OF LEONIA, NEW JERSEY, ASSIGNOR TO THE DIAMOND PRODUCTS CORPORATION, OF WILMINGTON, DELAWARE, A CORPORATION OF DELAWARE.

FIGURE TOY.

Application filed October 14, 1920. Serial No. 416,839.

To all whom it may concern:

Be it known that I, PETER S. H. NEWELL, a citizen of the United States, and resident of Leonia, in the county of Bergen and State 5 of New Jersey, have invented certain new and useful Improvements in Figure Toys, of which the following is a specification.

This invention relates to figure toys designed more especially for the amusement of 10 children; and the object of the invention is to provide a toy comprising a resiliently supported element or elements in simulation of a grotesque figure or figures, and means whereby various amusing motions can be 15 imparted to such figure or figures. In the present form of embodiment of my invention, two elements, representing a boy attacked posteriorly by a goose, are employed, the operative connections being such that by 20 their manipulation the elements can be so relatively moved that the "boy" is apparently making a desperate effort to escape while the "goose" holds him. Of course, the resiliently supported elements, and each of 25 them, may represent other objects or subjects to which the appropriate motions are imparted.

The invention, generally stated, comprises various novel features of construction and 30 combinations of parts which will be herein-after described and claimed.

In the drawings—

Figure 1 is a side elevation, partly in section, of a toy embodying one form of my 35 invention.

Fig. 2 is a plan of the structure.

Fig. 3 is a detail, enlarged, of a resilient neck connection between the two elements.

Referring to the drawings, 4 designates a 40 suitable base, which, in the present instance, is rectangular in plan, and is hollowed out in its under side, as at 5, and provided with a bottom 5', to constitute a suitable casing. Within this casing adjacent one end thereof, 45 is mounted an oscillatory member comprising preferably a disk or sheave 6 having a stud or pindle 7 which projects upwardly through a perforation in the top of the casing. Passed about the periphery of the 50 sheave and secured thereto, as at 8', is a looped cord 8, one end of which extends loosely through a perforation 9 in that end of the casing remote from the sheave, while the other extremity of the cord is attached 55 by means of a spring connection 10 to a pin

11 secured within the casing adjacent the perforation 9. Hence by variably pulling out the free end of the cord against the stress of the spring, and then permitting the spring to retract the cord, the sheave can be 60 oscillated on its axis to a greater or less extent and with more or less rapidity as the user may desire.

Supported on the up-projecting portion of the stud or pindle 7 is a suitable element 65 12, which, in the present instance, represents the grotesque figure of a boy having an integral posterior extension 13 in simulation of the head of a goose holding the boy. The body of the goose comprises an element 70 14 which is supported on the base by up-standing resilient legs constituted by tightly coiled springs 15. The neck of the goose is formed by a tightly coiled spring 16 having capacity for lateral deflection and longitudinal movement, which spring is rigidly secured at its extremities to end projections 75 17 on the head and body portions respectively, said spring 16 having relatively great resistance and being somewhat longer than 80 the distance between the head and body portions of the goose.

By the construction above described, it will be seen that when the sheave is oscillated by proper manipulation of the cord 8 85 as above mentioned, the element 12 will be oscillated on a vertical axis, and the motion will be transmitted therefrom to the yieldingly supported element 14 through the neck connection 16; such connection, as the associated parts are actuated, being caused by its 90 inherent elasticity to assume various bow-like or sinuous forms and thereby swinging the body of the goose to and fro on its elastic leg connections; the general effect being that 95 of the boy unsuccessfully striving to escape from the attack of the goose.

It is to be noted that the action of the spring 10 and its connections, is to maintain the elements 12 and 14 normally in the relative angular position shown by the full lines in Fig. 2, and that when the cord is pulled in opposition to the spring, said elements are swung to or towards the opposite position indicated by the dotted lines in Fig. 2. 100

It is to be understood that I do not limit my invention to the specific details of construction and arrangement nor to the particular configuration or configurations of the elements herein disclosed, as the struc- 105

ture and design may be variously modified within the principle of my invention and the scope of the appended claims.

I claim—

5. 1. A toy comprising a base, a figure element, upstanding resilient means supporting said element above the base, and comprising tightly coiled springs which normally sustain said element in upright position and yet permit its universal movement, oscillatory actuating means supported by the base, and operative connection between the said actuating means and the figure element.
10. 2. A toy comprising a base, a figure element, upstanding resilient means supporting said element above the base, and comprising tightly coiled springs which normally sustain said element in upright position and yet permit its universal movement, oscillatory actuating means, including a rotary member and operating devices therefor carried by the base, and a connection, including a resilient member, between the rotary member and the figure element.
15. 3. A toy comprising a base, a movable body, resilient legs connecting said body with the base, an oscillatory member supported by the base, means for actuating said member, and a connection, including a resilient member, between the said oscillatory member and the body, said resilient member having capacity for lateral deflection and longitudinal movement.
20. 4. A toy comprising a base, two figure elements thereon, one mounted to oscillate on a vertical axis, and the other mounted for universal movement, a connection, including a laterally and longitudinally resilient member, between the bodies of the two elements, and means for actuating the oscillatory element.
25. 5. A toy comprising a base, a figure element, upstanding resilient means supporting said element above the base, a second figure element, a connection, including a resilient member, between the two elements, an oscillatory actuating member supported by the base, and a connection, including a resilient member, between said actuating member and one of said figure elements.
30. 6. A toy comprising a base, two associated elements in grotesque simulation of an individual attacked by a goose, the head of the goose comprising an integral extension of the posterior of the individual, and the neck of the goose being constituted by a resilient connection, resilient legs connecting one element with the base, a pivotal connection between the other element and the base, and means for oscillating said pivotal connection.
35. 7. A toy comprising a base, two associated elements in grotesque simulation of an individual attacked by a goose, the head of the goose comprising an integral extension of the posterior of the individual, and the neck of the goose being constituted by a resilient connection, resilient legs connecting one element with the base, a pivotal connection between the other element and the base, means for oscillating said pivotal connection, said means including a rotary member, an operating string therefor, and a spring connection between one end of the string and the base.
40. 8. In a toy having a base, a movable element and a resilient connection between the said element and the base, means for imparting variable motion to said element comprising a rotary member carried by the base, operative connection between the said rotary member and the said element, an operating string flexed about the said rotary member and secured thereto, and a spring connection between one end of the string and the base.
45. Signed at New York, in the county and State of New York this 7th day of October A. D. 1920.

PETER S. H. NEWELL.
